UNITED STATES PATENT OFFICE.

CESARE PAROLINI, OF LE VESINET-SEINE ET OISE, AND GUSTAVE PERRON, OF PARIS,
FRANCE.

SOUND-REPRODUCING APPARATUS FOR DISK RECORD TALKING MACHINES.

Application filed May 16, 1924, Serial No. 713,677, and in France July 12, 1923.

The present invention relates to sound-reproducing apparatus of the conical diaphragm type comprising an inverted cone open at its base, the apex of which carries a 5 stylus mounted directly upon it and resting upon the record groove, or which is connected by an arrangement of levers to the said stylus, which latter may be a sapphire or a renewable needle.

10 The drawback of that kind of sound reproducers of this diaphragm type are that such apparatus must necessarily be of large dimensions in order to be capable of compensating for the absence of the usual amplifier sound horn or trumpet, thus necessitating the provision of devices for tensioning the walls of the cone in order to maintain it always taut in spite of the variations in temperature or the changes in the hydro- 15 metric state of the surrounding atmosphere, and also the use of devices for regulating the vibrations of the said walls for the purpose of obtaining the best possible reproduction of the sound.

20 25 The present invention has thus for its object to remedy the various drawbacks above-mentioned, and also to provide an improved sound reproducer of this diaphragm type which shall be audible in all directions, and it consists, for this purpose, in the combination of a conical diaphragm of the same kind and of the same materials as those already known, with an amplifying sound horn or trumpet of suitable shape, the connection between these two devices being effected at the open base of the diaphragm by means of a flexible member that will stop the vibrations of the conical wall of the diaphragm, so that these vibrations shall not 30 35 40 be transmitted to the wall of the sound horn or trumpet.

In order to enable the invention to be fully understood a constructional form thereof is hereinafter described and illustrated by way of example diagrammatically in diametral section in the accompanying drawing.

As shown, 1 is an inverted conical diaphragm open to the atmosphere; its base or wider edge is attached by means of an adhesive, or is fixed in any other manner, to a flexible rubber ring 2 to which there is likewise attached by means of an adhesive or fixed in any other manner the edge of an 55 amplifying sound horn or trumpet 3 (here-

inafter called the "conical amplifier") made of metal, and preferably of truncated conical form with a large opening or base and small depth.

Near the small end of the conical amplifier 3 are fixed the ends of a spider 4 of metal or other rigid material having two, three or four arms. This spider, which is arranged outside the diaphragm 1, and is situated close to the latter, comprises at its 50 centre at the intersection of its arms a ring or orifice 5 the centre of which coincides with the apex of the conical diaphragm 1, and through which passes freely the vertical portion of the rocking lever 6 connecting the 55 apex of the diaphragm 1 to the stylus 7. This lever 6 is mounted so as to rock on an axle 8 carried by a bearing eye 9 that is fixed to one of the arms of the spider 4.

The attachment of the end of the rocking 75 lever 6 to the apex of the conical diaphragm 1 (which is composed of a light but strong material such as strong paper, moulded plastic material, &c.,) may be consolidated by means of a conical metal reinforcing washer 80 10 to which the vertical upper end of the said lever 6 is riveted, soldered or otherwise fixed. For the purpose of supporting the entire reproducer of the diaphragm type improved according to this invention whilst 85 nevertheless allowing it to have free vertical and lateral play in order that it shall follow the undulations of the spiral groove of the record on the surface of the disks, any of the usual phonograph or other supports 90 may be employed, for instance the one shown which consists of a double ball-and-socket joint 11 fixed at one side to one, two or more points close to the base of the conical amplifier 3, and at its other side to a pillar bracket 95 12 mounted on the box enclosing the mechanism of the talking machine.

It is to be understood that the apparatus for attaching and holding the entire reproducer shall always be so situated as to be opposite the stylus 7 in one and the same vertical plane when it is being used for reproducing phonographic recording disks. For the reproduction of gramophone records, the point of attachment of the conical amplifier 105 3 must be shifted into a position in which the vertical plane passing through the said point of attachment and the centre or apex of the apparatus shall enclose an angle of about 90° with the vertical plane of the rock- 110

ing movement of the lever 6, since it is not absolutely necessary that the entire apparatus shall be maintained parallel to the surface of the record disk; in fact it may be given any desired inclination by altering the height of the joint 11.

As a constructional variant of the improved reproducer of the diaphragm type, and with relation to the reproduction of phonographic records, the apparatus may be simplified by fixing the stylus 7 directly to the apex of the conical diaphragm 1, which arrangement allows of dispensing with the spider 4, the ring 5 and the rocking lever 6.

It is to be understood that modifications, alterations and improvements may be made in the practical construction of the improved reproducer of the diaphragm type without thereby departing from the nature of the invention. For instance the solid or hollow rubber ring 2 may be replaced by a circular band of caoutchouc or fabric the two edges of which are respectively fastened to the edges or ends of the diaphragm 1 and conical amplifier 3 by means of an adhesive or in any other manner.

That what we claim is:

1. An acoustic device comprising a conical diaphragm having an open base, a frusto-conical amplifier horn having its smaller base approximately equal to and adjoining the open base of the diaphragm, said amplifier and diaphragm having a connection between their adjacent bases preventing the transmission of vibrations between them, and means connected to the diaphragm for imparting vibrations thereto.

2. An acoustic device comprising a conical diaphragm having an open base, a frusto-conical amplifier horn having its smaller base approximately equal to and adjoining the open base of the diaphragm, said amplifier and diaphragm having a connection between their adjacent bases preventing the transmission of vibrations between them, said connection including an interposed body of resilient rubber, and means connected to the diaphragm for imparting vibrations thereto.

3. An acoustic device comprising a conical diaphragm having an open base, a frusto-conical amplifier horn having its smaller base approximately equal to and adjoining the open base of the diaphragm, a ring of resilient rubber interposed between and connected to the adjacent bases of said amplifier and diaphragm, and means for causing vibrations of said diaphragm.

4. An acoustic device comprising a conical diaphragm having an open base, a frusto-conical amplifier horn having its smaller base approximately equal to and adjoining the open base of the diaphragm, said amplifier and diaphragm having a connection between their adjacent bases preventing the transmission of vibrations between them, a frame connected to the amplifier and extending into proximity to the apex of the diaphragm, and means supported by said frame and connected to the apex of the diaphragm for imparting vibrations to said diaphragm.

In witness whereof, we hereunto subscribe our signatures.

CESARE PAROLINI.
GUSTAVE PERRON.
